UNITED STATES PATENT OFFICE.

CARL C. SEVERIN, OF SAN FRANCISCO, CALIFORNIA.

DESIGN FOR AN ELECTRIC-LIGHT FIXTURE.

Application filed August 14, 1924. Serial No. 10,462. Term of patent 7 years.

To all whom it may concern:

Be it known that I, CARL C. SEVERIN, a citizen of the United States, residing at the city and county of San Francisco and State of California, have invented a new, original, and ornamental Design for Electric-Light Fixture, of which the following is a specifi-

cation, reference being had to the accompanying drawing, forming part thereof.

The figure is a side elevation of the same.

I claim:

The ornamental design for an electric light fixture, as shown.

CARL C. SEVERIN.
